[57] CLAIM

The ornamental design for wrist or ankle weight, as shown and described.

DESCRIPTION

FIG. 1 is a view in end elevation of the wrist or ankle weight of this invention in wrapped-around condition;

FIG. 2 is a view in side elevation viewed from lower to upper side FIG. 1;

FIG. 3 is a view in side elevation from the diametrically opposite side as shown in FIG. 2.

FIG. 4 is a bottom plan view of the wrist or ankle weight in its unwrapped condition;

FIG. 5 is a view in side elevation of the device as shown in FIG. 4, the other side being a mirror image of the side shown in FIG. 5.

FIG. 6 is a top plan view;

FIG. 7 is a view in end elevation in the direction from bottom to top of FIG. 6; and,

FIG. 8 is a view in end elevation of the device shown in FIG. 6.
